(57) **CLAIM**

The ornamental design for a bottle pourer, as shown and described.

DESCRIPTION

FIG. 1 is a front elevation view of a bottle pourer showing my new design; the rear being a mirror image thereof; FIG. 2 is a left side elevation view of the bottle pourer of FIG. 1;

FIG. 3 is a right side elevation view of the bottle pourer of FIG. 1;

FIG. 4 is a top view of the bottle pourer of FIG. 1;

FIG. 5 is a bottom view of the bottle pourer of FIG. 1; and, FIG. 6 is a top perspective view of the bottle pourer of FIG. 1.

The broken lines illustrate environmental structure and form no part of the claimed design.
